(57) **CLAIM**

The ornamental design for multi-layered sample cassette, as shown and described.

DESCRIPTION

FIG. 1 is a top, front, right side perspective view of a first embodiment of the multi-layered sample cassette;

FIG. 2 is a top plan view of the embodiment of FIG. 1;

FIG. 3 is a bottom plan view of the embodiment of FIG. 1;

FIG. 4 is a front elevational view of the embodiment of FIG.

1;

FIG. 5 is a rear elevational view of the embodiment of FIG.

1;

FIG. 6 is a left side elevational view of the embodiment of FIG. 1;

FIG. 7 is a right side elevational view of the embodiment of FIG. 1;

FIG. 8 is a top, front, right side perspective view of a fourth embodiment of the multi-layered sample cassette;

FIG. 9 is a top plan view of the embodiment of FIG. 8;

FIG. 10 is a bottom plan view of the embodiment of FIG. 8;

FIG. 11 is a front elevational view of the embodiment of FIG. 8;

FIG. 12 is a rear elevational view of the embodiment of FIG.

8;

FIG. 13 is a left side elevational view of the embodiment of FIG. 8; and,

FIG. 14 is a right side elevational view of the embodiment of FIG. 8.

The broken lines are included for the purpose of illustrating portions of the multi-layered sample cassette that form no part of the claimed design.
